DESIGN FOR A DRESS AND SCARF ENSEMBLE

Samuel Chapman, New York, N. Y.

Application March 15, 1938, Serial No. 75,832

Term of patent 3½ years

To all whom it may concern:

Be it known that I, Samuel Chapman, a citizen of the United States of America, residing in New York city, in the Borough of Manhattan, county and State of New York, have invented a new, original, and ornamental Design for a Dress and Scarf Ensemble, of which the following is a specification, reference being had to the accompanying drawing, forming part thereof, wherein,

The characteristic feature of my design resides in the combination on the evening gown disclosed, of the particular front and rear waist sections, which are seamed and Shirred in the manner disclosed, in combination with a detachable two-piece scarf, as shown.

I claim:

The ornamental design for a dress and scarf ensemble, substantially as shown and described.

SAMUEL CHAPMAN.
